CLAIM

The ornamental design for a blanket, as shown and described.

DESCRIPTION

FIG. 1 is a front view of a blanket showing our new design; FIG. 2 is a rear view thereof; FIG. 3 is a right side view thereof; FIG. 4 is a left side view thereof; FIG. 5 is a top view thereof; FIG. 6 is a bottom view thereof; and, FIG. 7 is an enlarged view of the region identified by the number "7" in FIG. 2 thereof.

The broken lines within the shaded area represent stitching. The broken lines immediately adjacent to the shaded area define the bounds of the claimed design and form no part thereof. The broken lines depicting the remainder of the blanket show features that form no part of the claimed design.
